HENRY WHITTEMORE, OF PASSAIC, NEW JERSEY.

Design No. 4,345, dated September 6, 1870.

DESIGN FOR A CURTAIN-CORNICE, &c.

The Schedule referred to in these Letters Patent and making part of the same

I, HENRY WHITTEMORE, of Passaic, in the county of Passaic and State of New Jersey, have invented a new Design for a Curtain-Cornice and Screen-Canopy, of which the following is a specification.

Hitherto cornices for drapery have been made to project from the wall at the angle, so as to present the same finish at the ends as upon the front, or, if composed of a simple molding, by supporting it at some distance from the wall, so as to leave a space behind the drapery.

Those made in the manner first described are expensive, while the others are unfinished and inferior looking.

My improved design has for its object the production of a flat cornice, which may hang against the wall, and yet admit of the drapery being thrown out or removed therefrom, when access is required for sweeping, or other purposes behind it, and that will, at the same time, admit of expanding, to cover double the width, when required, or to drape the sides of an alcove or recess, when placed in one; and it has relation, also, to cheapness of cost, and to being applied or suspended by simple means, and without the aid of a mechanic.

It is designed especially for attaching screens for the protection of the walls over wash-stands and permanent basins, but it is equally adapted for the draping of windows, alcoves, and arches.

I form the body or main portion of the cornice of a plain, flat piece of wood, preferably of ash or other light color, A, fig. 1, which may be rendered more ornamental by a band, b, of darker wood, and the face may be relieved by rosettes or panels c c, of a contrasting wood.

The top edge of the part A has a pediment, f, to give a more agreeable outline, which may be ornamented in like manner, and at the lower edge, pivoted to each end, are two arms, g g, finished with a pendant at the end, and diminishing in a curve as they approach each other at the center.

These arms are movable on the pin by which they are affixed, so as to swing outward, and either remain at right angles, if used in an alcove, or be turned around on a plane with the cornice, as represented in fig. 2, and thereby cover a larger space on the wall.

Figure 1 represents a cornice in front elevation, the dotted lines indicating the drapery; and

Figure 2, a plan or top view, with the arms g g thrown out.

In this view the dotted lines e e indicate the top of a wash stand, showing the cornice and drapery, as applied as a protecting screen for the wall.

Figures 3 and 4 show the mode of attaching to the wall, which is very simple.

A screw-ring, i, is inserted at each of the upper corners of the part A, and pins h h are driven into the wall, over which the rings are slipped.

A turned ornament or rosette, j, is then screwed on the outer end of the spike, (which is provided with a thread,) and this conceals the means by which the cornice is hung, and forms an appropriate ornament for the ends of the pediment, as seen in fig. 1.

The method of attaching the drapery is very easy.

A cord, l, is attached by wire staples to the back side of the portion A, and also of the wings g g, on which the drapery is hung in the usual manner.

When employed for windows, the lambrequin portion is attached to the arms, and the embroidery to the main cornice, or, if preferred, double wires may be used, and both attached to the arms, so that the whole drapery can be removed when the window requires to be brushed, or for the admission of air, when the sash is opened at the top.

When used as a wash-stand screen, the drapery may be of any material suitable to protect the wall, and should be attached the back screen to the part A, and the side portions only to the wings, when it is capable of serving for an alcove, by turning the wings outwardly, or for covering a wider portion of the wall by swinging them clear around.

In form it is ornamental, and adapted to form a suitable ornamental finish to a wash-stand, or to a window or alcove, while the method of construction makes it inexpensive and simple in its application and use.

I claim—

As a design for suspending draperies for wash-stand screens, windows, &c., the flat cornice A, provided with the arms g g, of the form and configuration herein shown and described.

In witness whereof I have hereunto signed my name in the presence of two subscribing witnesses.

Witnesses: HENRY WHITTEMORE.

W.M. F. McNAMARA,

KATE N. JONES.
